UNITED STATES PATENT OFFICE

FRANKLIN H. BROWN, OF PHILADELPHIA, PENNSYLVANIA, ASSIGNOR TO CUP-LOK
PACKING COMPANY, OF PHILADELPHIA, PENNSYLVANIA, A CORPORATION OF
DELAWARE

STUFFING BOX LOADER

Application filed January 6, 1931. Serial No. 506,949.

This invention relates to stuffing box loaders and particularly to a loader including a barrel wherein the packing for the stuffing box may be placed, the barrel having a movable plunger whereby the packing for the stuffing box may be forced into the stuffing box.

The general object of this invention is to provide a very simple and strong loader of this character whereby stuffing boxes may be kept filled with packing and as the packing in the stuffing box is worn, new packing forced into place.

A further object is to provide a device of this character particularly adapted to be used where there is back pressure such as steam pressure, and which is so constructed that this back pressure or fluid pressure may be shut off from access to the loading barrel to permit the plunger of the loading barrel to be removed, packing inserted therein and the plunger replaced, communication then being established between the barrel and the stuffing box.

A further object in this connection is to provide a slide mounted upon the stuffing box and carrying the barrel and plunger, which slide is capable of being shifted to carry the loading barrel out of a position in alinement with the stuffing box opening, the slide acting to close the opening under the circumstances and prevent the escape of pressure from the stuffing box, the slide, of course, being shiftable reversely to carry the packing, after the barrel has been filled with plastic packing, into a position registering with the stuffing box opening.

Other objects will appear in the course of the following description.

My invention is illustrated in the accompanying drawings, wherein:—

Figure 1 is an elevation of a stuffing box and loader therefor, the loader being constructed in accordance with my invention.

Figure 2 is a plan view of the structure shown in Figure 1, and

Figure 3 is a section on the line 3—3 of Figure 1.

Referring to these drawings, A indicates a stuffing box or gland of any suitable char-

acter and a an opening through which packing may be inserted in the stuffing box. Swingingly mounted upon one face of the gland or stuffing box is the slide 10 which is illustrated as segmental in form. This is pivoted upon the face of the stuffing box by means of a cap screw 11, the upper face of the stuffing box being surfaced so that the slide and stuffing box have close engagement with each other. The free end of the slide 10 is formed with an arcuate slot 12 through which another cap screw 13 passes. By turning these cap screws down, the plate or slide 10 may be forced into tight engagement with the face of the stuffing box and by loosening the screw 13, the slide may be released so that it may be shifted.

Mounted upon the slide is the loading barrel 14 whose interior diameter is the same as that of the opening a and which is so disposed upon the slide that it may be moved into a position of registry with the opening a. The upper end of the barrel 14 is closed by a screw threaded cap 15, this cap being annular in plan and having interior screw threads engaging with screw threads on a plunger 16. This plunger at its upper end has a head whereby a wrench may be applied and the lower end of the plunger carries the swivelled head 17, the under face of which is slightly concave.

When it is necessary to replenish the packing within the barrel 14, the screw 13 is loosened and the segmental slide shifted so as to carry the barrel out of alinement with the opening a. The slide is only shifted sufficiently to entirely close the opening a by the slide itself. Then the cap 15 is removed together with the plunger, the barrel is filled with plastic packing, the plunger retracted to its full extent, the cap 15 replaced upon the barrel; then the slide is again shifted to bring the barrel in alinement with the opening a and the screw 13 again tightened. Then, from time to time, as necessary, packing may be forced into the stuffing box or gland. In this device, when at any time more packing is necessary, the plunger screw is turned downward, forcing the packing equally into the stuffing box and preventing

all leaks. It is to be particularly noted that this plunger has a relatively large plunger head 17. In other loaders known to me, a set screw is used to force the packing into position, the set screw being pointed, which causes the packing to fill into the threads and jam. By this means, glands or stuffing boxes may be packed, in which there is back pressure or fluid pressure and the loading barrel 10 may be refilled without any danger of the pressure being lost while doing so.

It will be noted that the slot 12 is of such length that when the screw 13 is at one end of the slot, the loading barrel will be in exact alignment with the opening *a* and that when the plate has been shifted so that the screw 13 is at the other end of the slot, the opening *a* will be cut off by the plate. Thus the slot not only provides means whereby the plate 20 may be clamped tight down against the face of the stuffing box, but also means to indicate definitely whether the loading barrel is in alignment with the opening *a* or fully out of registry therewith.

It is to be particularly noted that in my loader, the screw 16 is considerably less in diameter than the interior of the diameter of the loading barrel 14 and that this screw 16 has threaded engagement with the cap 15 and 30 not with the interior of the barrel. I have found in actual practice that where a plunger of this character has threaded engagement with the interior of the face of the barrel, that the pressure induced by the plunger will cause the packing to be forced upward through the threads between the plunger and barrel and thus reduce the pressure on the packing and act to clog or prevent the easy turning movement of the screw. I have illustrated a head 17 which is swivelled to the plunger 16, but I do not wish to be limited to this as the head might be made rigid with the plunger 16. I find, however, that the swivelled head is preferable, for the reason 40 that the head does not turn with the turning movement of the plunger and does not act to twist the packing disposed below the plunger or otherwise distort it but that the pressure is straight inward into the gland or 50 stuffing box.

The plate 10 slidably mounted upon the upper face of the gland or stuffing box is particularly designed to be used in those cases where there is back pressure but in case there is no back pressure, it is within the purview of my invention to leave off this plate and connect the loading barrel directly to the stuffing box or like element.

Actual use has demonstrated that this 60 stuffing box loader is of particular advantage and particularly effective in actual practice and by its means, packing may from time to time be forced into the stuffing box or gland without any chance of the hands of the operator becoming contaminated with the pack-

ing or by grease or anything of that nature and furthermore, the pressure induced by the screw is sufficiently great so that the hardest packing, provided it be plastic at all, may be forced into the stuffing box and fully pack the 70 same.

Having described my invention, what I claim is:—

1. The combination with a stuffing box having an opening, of a supporting plate slidably mounted upon the stuffing box, a loading barrel mounted upon the plate and adapted when the plate is shifted into one position to register with the opening in the stuffing box, the plate acting to close the opening in the stuffing box when the barrel is shifted out of a position of registry with said opening, and a plunger mounted within the barrel. 75

2. The combination with a stuffing box having an opening, of a supporting plate slidably mounted upon the stuffing box, a loading barrel mounted upon the plate and adapted when the plate is shifted into one position to register with the opening in the stuffing box, the plate acting to close the opening in the stuffing box when the barrel is shifted out of a position of registry with said opening, a plunger mounted within the barrel having screw threaded engagement with the barrel. 80

3. The combination with a stuffing box, of a plate slidably mounted upon one face of the stuffing box, the stuffing box having an opening, a loading barrel mounted upon the plate and adapted when the plate is shifted into one position to register with the opening in the stuffing box, said plate acting when shifted out of this position to close the opening in the stuffing box, a cap mounted upon the outer end of the barrel, and a plunger having screw threaded engagement with the cap. 95

4. The combination with a stuffing box, of a plate slidably mounted upon one face of the stuffing box, the stuffing box having an opening, a loading barrel mounted upon the plate and adapted when the plate is shifted into one position to register with the opening in the stuffing box, said plate acting when shifted out of this position to close the opening in the stuffing box, a cap mounted upon the outer end of the barrel, and a plunger having screw threaded engagement with the cap, said plunger having a swivelled head. 100

5. The combination of a stuffing box having an opening, of a plate pivotally mounted upon the face of the stuffing box, the plate having a slot concentric to the pivot, a screw passing through the slot into the stuffing box, a loading barrel mounted upon said plate and adapted when the plate is shifted in one position to register with the opening in the stuffing box, said plate acting when shifted in another position to close the opening in the stuffing box, and a plunger having a screw threaded operative engagement with 110

the loading barrel and having a swivelled plunger head.

6. The combination with a stuffing box having a filling opening, of a segmental plate disposed upon one face of the stuffing box 5 and having an arcuate slot, a pivot screw passing through one end of the plate and into the stuffing box, a screw passing through the slot in the plate and into the stuffing box, a loading barrel mounted upon the plate and 10 adapted to be brought into registry with the opening in the stuffing box, and a plunger having screw threaded engagement with the loading barrel.

7. A stuffing box loader comprising a supporting plate adapted to be mounted upon the face of a stuffing box, means for shiftingly mounting the plate upon the face of the stuffing box, a loading barrel mounted upon the plate and adapted when the plate is shifted 15 into one position to register with the opening in the stuffing box, the plate acting when shifted into another position to close the opening in the stuffing box and a plunger having screw-threaded engagement with the 20 loading barrel.

In testimony whereof I hereunto affix my signature.

FRANKLIN H. BROWN.
